UNITED STATES PATENT OFFICE.

EDWARD HIXON, OF CHICAGO, ILLINOIS.

ELECTROLYZER.

No. 927,970.

Specification of Letters Patent.

Patented July 13, 1909.

Application filed February 25, 1909. Serial No. 479,906.

To all whom it may concern:

Be it known that I, EDWARD HIXON, a citizen of the United States, and a resident of Chicago, in the county of Cook and State 5 of Illinois, have invented a new and Improved Electrolyzer, of which the following is a full, clear, and exact description.

This invention relates to certain improvements in electrolyzing apparatus, and more 10 particularly to an apparatus for effecting the solution of a chemical and the electric decomposing of the resulting electrolyte.

The special apparatus illustrated is particularly designed for use in the manufacture 15 of a bleaching liquid, although it is, of course, evident that it might be used for other purposes.

The invention consists in the details of construction and combination of parts hereinafter described and particularly pointed out in the claims.

Reference is to be had to the accompanying drawings, forming a part of this specification, in which similar characters of reference indicate corresponding parts in all the 25 figures, and in which—

Figure 1 is a top plan view of an apparatus constructed in accordance with my invention; Fig. 2 is a vertical longitudinal 30 section on the line 2—2 of Fig. 1; Fig. 3 is a longitudinal section through the electrolyzing apparatus proper, said section being taken on the line 3—3 of Fig. 4; Fig. 4 is a top plan view of the electrolyzing apparatus proper; and Fig. 5 is a transverse 35 section on the line 5—5 of Fig. 4.

In my improved electrolyzer, I employ three separate containers or receptacles 10, 11 and 12, all mounted on the same standard 40 and so arranged that the liquid may flow from one to another through the series. My improved standard includes four corner posts 13, each preferably formed of an angle iron and connected together by transversely-extending angle irons 14 intermediate the top and bottom of the frame, and longitudinally-extending angle irons 15 at the upper end of the frame. The tank or receptacle 12, which is the lowest of the series, extends 45 longitudinally of the frame and is supported directly upon the angle irons 14.

Directly above the tank 12 and also supported within the frame is the tank 10, hereinafter referred to as the "mixing tank." 50 This tank is substantially semi-cylindrical in form and is supported by transversely ex-

tending curved bands 16, the upper ends of which are connected to the longitudinally-extending angle irons 15. The mixing-tank 10 is preferably formed of metal and within the tank and extending longitudinally thereof is an agitator 17 for thoroughly mixing the material to be dissolved with the solvent.

The agitator preferably has a plurality of substantially parallel blades or wings 18 rotatable about a central shaft, and one end of this shaft extends to the exterior of the tank and is provided with a pulley 19 for rotating the same. The shaft and agitator are parallel to the bottom of the tank, and the shaft is so disposed that the blades come closely adjacent the lowermost portion of the tank as they move about their axes. The mixing tank 10 is preferably open at the top and at one end it may have a gage glass 20 connected to the top and bottom of the tank for clearly indicating the quantity of liquid within the tank.

At one end of the main tank is a support or bracket constituting an auxiliary frame 80 and formed of horizontally-disposed angle irons 21 extending outwardly substantially parallel from two of the corner posts and connected together by transversely-extending angle irons 22, one adjacent the outer ends 85 of the angle irons 21 and the other closely adjacent the two end posts. Angle irons 23 are connected to the outer end of this auxiliary frame and extend downwardly diagonally to the lower portion of the two corner 90 posts, so as to serve as a bracket or support for the platform formed by the angle irons 21 and 22. Mounted upon this platform and held against lateral movement by the angle irons 22, is the electrolyzing tank 11. A 95 draw-off pipe 24 leads from one end of the mixing tank 10, adjacent the bottom thereof, to one end of the electrolyzing tank 11, and a draw-off pipe 25 leads from the opposite end of the electrolyzing tank to the liquor 100 tank 12. The electrolyzing tank is provided with a series of vertically-disposed cleats or ridges 26 upon opposite sides, which form between them a series of vertical grooves or channels. The interior of the electrolyzing 105 tank is subdivided by a plurality of substantially parallel vertical partitions 27, the ends of which are disposed between adjacent cleats or ridges 26. The partitions are vertically removable from the casing, and each 110 is preferably formed of graphite or other suitable material which will be unaffected by

the action of the chemicals employed or an electric current. Each alternate partition is cut away at one lower corner to form an opening or passage 28, and the remaining partitions are cut away at the upper opposite corner to form passages 29. The liquid which enters at one end of the electrolyzing tank must thus flow through a passage 28 at the lower corner of one partition and thence not only upwardly but also transversely to the diagonally opposite corner of the next partition, to pass through an opening 29. The liquid thus travels in a zigzag course not only transversely but also vertically in the electrolyzing tank 11, from the inlet conduit 24 to the outlet conduit 25. The partitions which subdivide the tank into a conduit may be made of graphite, and said partitions are preferably formed of a plurality of slats or bars 30, each extending transversely of the tank, and all of the bars of one partition being in vertical alinement. A top bar 31 of glass may be employed upon each alternate partition, that is, the ones having the lower openings 28, to preclude the possibility of any of the liquid traveling over the top of these partitions. At the ends of the electrolyzing tank, I insert two electrodes, each formed of a plurality of vertically-disposed slats or bars 32 of carbon, connected together across the top by a connecting piece 33. This connecting piece is above the level of the tank, and is preferably of metal and carries a binding post 34, to which a wire from a suitable source of electrical energy is connected.

In the operation of my improved apparatus, common salt, that is, chlorid of sodium, is placed in the dissolving or mixing tank 10, together with a sufficient quantity of water, and the agitator is started in operation to facilitate the solution of the salt in the water. When the solution of the desired strength has been obtained, the liquid is permitted to slowly escape through the conduit 24 to one end of the electrolyzing tank, and thence longitudinally of the tank to the outlet therefrom. Wires from a suitable source of electrical energy are connected to the two electrodes at opposite ends of the tank 11, and a current is caused to flow from one electrode to the other through the liquid in the direction of flow. The solution and the current travel in the same direction through the open spaces between the plates, and the rate of flow and the strength of current is so regulated that the solution has the proper qualities at the time it reaches

the outlet conduit 25. The salt is first decomposed to separate the sodium and chlorin, which collect at the opposite electrodes. The sodium set free from combination with the chlorin, combines with the oxygen and part of the hydrogen, and becomes converted into sodium-hydroxid or caustic soda. This results from a partial decomposition of the water, and hydrogen gas escapes at the electrode. The chlorin liberated at the opposite electrode will combine with a portion of the caustic soda in solution, to form a hypochlorid, which in turn will be converted into a chlorin of sodium.

Various other chemical reactions take place, the exact nature of which it is difficult to accurately determine. The solution which escapes at the outlet conduit 25 and collects in the tank 12, is the proper solution desired for use as a bleaching liquid. The tanks 11 and 12 are formed of material which will be unaffected by electric current or by the various compounds produced; porcelain has been found very suitable for the purpose.

Having thus described my invention, I claim as new and desire to secure by Letters Patent:

1. An electrolyzing apparatus, comprising a mixing tank, an electrolyzing tank, a receiving tank, and pipe connections between said tanks, said electrolyzing tank having a plurality of vertically-disposed transverse partitions removably mounted therein, certain of said partitions having openings therethrough at the bottom thereof and the remainder of said partitions having openings therethrough at the top thereof.

2. An electrolyzing apparatus, comprising a mixing tank, an electrolyzing tank, a receiving tank, pipe connections between said tanks, said electrolyzing tank having a plurality of vertically-disposed transverse partitions removably mounted therein, certain of said partitions having openings therethrough at the bottom thereof adjacent one end and the remainder of said partitions having openings therethrough adjacent the top at the opposite end, and electrodes within said tank adjacent opposite ends.

In testimony whereof I have signed my name to this specification in the presence of two subscribing witnesses.

EDWARD HIXON.
